by Emil Schatz, Atty.

UNITED STATES PATENT OFFICE.

CLAUDIUS DORNIER, OF FRIEDRICHSHAFEN-ON-THE-BODENSEE, GERMANY.

WING OF FLYING MACHINES.

Application filed May 15, 1924. Serial No. 713,503.

To all whom it may concern:

Be it known that I, CLAUDIO DORNIER, a citizen of Germany, residing at Friedrichshafen-on-the-Bodensee, Germany, have invented certain new and useful Improvements in Wings of Flying Machines, of which the following is a specification.

My invention refers to the wings and supporting surfaces of flying machines. It is an object of my invention to provide wings or supporting surfaces which, while being as strong as the strongest planes hitherto constructed, can be manufactured and handled and mounted more easily.

15 Wings or supporting surfaces forming an undivided whole involve the drawbacks that certain points and more especially the joints inside the supporting surface are not easily accessible. Moreover, such supporting surfaces, owing to their larger size, cannot be handled easily and are liable to be damaged during transport and when being mounted. It has been tried to avoid these drawbacks by constructing the wings in several parts 20 which are then assembled together. However, such wings, although offering certain advantages regarding transporting and mounting, are inferior in strength and for this reason have not been adopted for use 25 to a larger extent.

The wings or supporting surfaces according to the present invention are composed of several parts assembled together, but in contradistinction to the supporting surfaces 30 mentioned above, they are as strong as any supporting plane in one part, while they offer great advantages by being easily taken to pieces, the single parts being easily exchanged and all parts of the material of 35 the surface being easily accessible.

The wing or supporting surface, according to the present invention, comprises a main portion of or shape, the spars representing the main ribs forming the outer surfaces of said main portion. The gaps between the middle web and the lateral edges of the ribs are filled up by separate self-contained sectional members which can easily be disengaged and exchanged, each sectional member forming a self-contained unit which can be manufactured independently of the other members and of the main portion. This latter, as well as the several sectional members, are 45 provided each with its own covering. The sectional members are fixed in place on the

main portion for instance by means of screw bolts inserted in eyes arranged on adjacent edges of the main body and the sectional members, respectively. It is, however, 50 also possible to arrange the sectional members hinged at the outer ends of the wings in order to be able to operate them as ailerons. In special cases, for instance where the transport offers particular difficulties, 55 that portion of the wing which extends in front of the transverse beams can form a self-contained, easily disengageable unit.

In the drawings affixed to this specification and forming part thereof, wings or supporting surfaces embodying my invention are illustrated diagrammatically by way of example. In the drawings—

Fig. 1 is a partial plan view,

Fig. 2 a partial front view with the sectional members removed and

Fig. 3 a cross section of the first modification, while

Fig. 4 is a partial plan view of a second modification.

Fig. 5 is a front view and

Fig. 6 a side view showing the way in which the sectional members are fixed in place.

Referring to the drawings, *a* is the middle web of the main body of the wing and *b*, *b* are ribs extending on both sides of the middle web and at right angles to it, while *c*, *c* are self-contained sectional members, filling the gaps between the middle web *a* and the ribs *b*.

In the modification shown in Fig. 4, the ribs *b* with sectional members *c* inserted between them extend only on one side of the middle web *a* and the entire front portion or head *d* of the wing forms a self-contained unit which is attached to the middle web *a* in a disengageable manner.

As shown more particularly in Figs. 5 and 6, the sectional members *c* are fixed in place between the ribs *b* by means of screw bolts extending through eyes *e* provided to this end on adjoining edges of the ribs and the sectional members.

If the ribs *b*, instead of being made in one piece with the middle web *a*, are disengageably fixed to it, the middle web, after the ribs *b*, *b* and sectional members *c*, *c* have been removed, will form a comparatively narrow rectangular body which can easily be transported.

I wish it to be understood that I do not

desire to be limited to the exact details of construction shown and described; for obvious modifications will occur to a person skilled in the art.

I claim:—

1. A wing or supporting surface for flying machines comprising a middle web, ribs extending from said middle web substantially at right angles thereto, a self-contained sectional member filling the gap between said middle web and said ribs and means for fixing said member in place between said ribs in an easily disengageable manner.
- 10 2. A wing or supporting surface for flying machines, comprising a middle web, ribs extending on either side and at right angles to said middle web, self-contained sectional members mounted between said middle web and said ribs and means for disengageably fixing said members to said ribs.
- 15 3. A wing or supporting surface for flying machines, comprising a middle web, ribs extending from said middle web on one side thereof at right angles thereto, a self-contained sectional member filling the gap between said middle web and said ribs, a head portion forming a self-contained unit being disengageably fixed to said middle web on the other side thereof and means for disengageably fixing said members to said ribs.

4. A wing or supporting surface for flying machines, comprising a middle web, ribs extending from said middle web substantially at right angles thereto, a self-contained sectional member filling the gap between said middle web and said ribs and means for fixing said member in place between said ribs in an easily disengageable manner, the covering of said insert being separate from the covering of said middle web and ribs.

5. A wing or supporting surface for flying machines, comprising a middle web, ribs extending from said middle web substantially at right angles and being removably fixed thereto, a self-contained sectional member filling the gap between said middle web and said ribs and means for fixing said member in place between said ribs in an easily disengageable manner.

6. A wing or supporting surface for flying machines comprising a middle web, ribs extending from said middle web substantially at right angles thereto, a self-contained sectional member filling the gap between said middle web and said ribs and means for attaching said member in place between said ribs in such manner that it can be rocked for use as an aileron and can also be disengaged altogether from said middle web.

In testimony whereof I affix my signature.
CLAUDIUS DORNIER.
